UNITED STATES PATENT OFFICE

CLEMENT A. LEGER, OF LINCOLN, NEBRASKA

LEVEL

Application filed May 29, 1931. Serial No. 540,976.

This invention relates generally to devices for determining by action of the force of gravity, the angularity of surfaces with respect to the horizontal, and particularly to 5 a new and novel embodiment of this principle which possesses features of novelty and advantage not heretofore discovered or applied as set out in the structure described below.

10 It is an object of this invention to provide an extremely simple device of this character which may be applied to a great variety of different instruments for determining angularity with respect to the horizontal.

15 This and other objects of the invention, its nature, and its composition and arrangement and combination of parts will be readily understood by anyone acquainted with the art to which this invention relates upon consulting the following descriptions of the drawing, in which:—

20 Figure 1 is a general side elevational view of one embodiment of the device of my invention shown in position on an angular surface.

Figure 2 is an enlarged detail side elevational view of the active element of the device of the invention.

25 Figure 3 is a longitudinal vertical sectional view through Figure 2.

Figure 4 is an enlarged elevational view of the end of the device of the invention opposite that portion thereof shown in Figure 2.

Referring in detail to the drawing the 30 numeral 5 generally designates a preferred form of the invention which consists of a flat elongated base 6 upon which is secured a metallic or other composition plate 7 having variously co-ordinated series of mathematical data usable in connection with the movable parts of the device to facilitate calculations in connection with the angularities measured by the said moving parts. The said series of data are generally indicated at 8.

35 The base 6 is at one end provided with a circular recess 9. The plate 7 is circularly apertured concentrically with the recess 9 as indicated at 10, the opening 10 being smaller than the recess 9 in order to confine within the 40 recess a disk 11. The disk 11 is slightly

smaller in diameter than the recess 9 and of a thickness less than the depth of the recess 9. A button 12 has L-shaped spring legs 13 extending downwardly then radially outwardly therefrom, the vertical portions 14 of the spring legs 13 being disposed in a central aperture in the disk 11. The elongated portions of the legs 13 contact the floor of the recess 9 and by spring action press the disk 11 outwardly into contact with the underside of the portion of the plate 7 over the recess, whereby to frictionally arrest a ball 15, which is disposed in a raceway 16 in the form of an annular recess in the upper face of the disk 11, the ball being pressed against the underside of the plate 7 by this action of the springs 13 of the button 12. The ball 15 when released by an inward pressure upon the button 12, is free to roll in the raceway 16, and this fact is taken advantage of to measure the angularity of a portion of a building, such as a roof or the like, or any other angularly disposed structure. The method of arriving at the angularity of an angularly disposed surface is to place the device of the invention as in Figure 1, on one edge thereof. Then the button 12 is pushed inwardly so as to release the ball 15 from frictional contact with the underside of the plate 7 over the recess 9, and the ball will be carried by gravity to the bottom of the raceway and indicate graphically in connection with indicia 17 placed around the aperture 10 in the plate 7, whereby to enable the determination in degrees or in other significant characters the degree of angularity of the upper edge of the device with the horizontal. Of course, the knowledge of this angularity permits coordination with knowledge of a definite length of base in a triangle, for instance, whereby to determine the height of a gable or the like, or any similar or generically related calculations may be made conveniently in connection with the coordinated series of data 8 placed on the surface of the plate 7.

45 As it is evident the device of the invention could be incorporated in a great variety of angle finding instruments, such as a sextant and the like, it is, therefore, to be definitely understood that I do not desire to 50

limit the application of this invention to the particular modification set out herein to illustrate the principles thereof, and any change or changes may be made in material and structure and arrangement of parts consistent with the spirit and scope of the invention.

What is claimed is:—

- 10 1. A device of the character described for measuring angles with the horizontal by gravity actuated means, comprising a base having a circular recess in one side near one end, a disk in the recess having a circumferential ball race, a ball in the race, and releasable spring means for normally positioning said disk so as to frictionally engage the ball with the base to prevent movement of the ball and operable to release the ball to permit it to fall and roll in said raceway to the lowest point thereof to indicate gravitationally the angularity of the base with the horizontal.
- 15 2. A device for gravitationally measuring angles comprising a base having a circular recess near one end, a plate on the base having an opening smaller than the opening of the recess and registered therewith, a disk in the recess having in its outward side an annular channel, a ball in the channel, and spring means normally moving said disk outwardly to press said ball against the plate, and other means projecting through the disk to act upon said spring means to permit the ball to roll freely in the channel and position itself at the lowest point of the channel to indicate the angularity of the base with the horizontal, said spring means adapted to retain the ball so positioned upon release thereof.
- 20 3. A device for gravitationally measuring angles comprising a base having a circular recess near one end, a plate on the base having an opening smaller than the opening of the recess and registered therewith, a disk in the recess having in its outward side an annular channel, a ball in the channel, and spring means normally moving said disk outwardly to press said ball against the plate, and other means projecting through the disk to act upon said spring means to permit the ball to roll freely in the channel and position itself at the lowest point of the channel to indicate the angularity of the base with the horizontal, said spring means adapted to retain the ball so positioned upon release thereof, and coordinated series of related mathematical tables in said plate adapted to cooperate with the indications made by the ball to give required solutions of problems.
- 25 4. In testimony whereof I affix my signature.
CLEMENT A. LEGER.
